DOOR-LATCH-OPERATING MECHANISM.

1,234,938.

Specification of Letters Patent.

Patented July 31, 1917.

Application filed March 6, 1917. Serial No. 152,739.

To all whom it may concern:

Be it known that we, RICHARD J. ROULO and CLAUDE L. ROULO, citizens of the United States, residing at Los Angeles and Oakland, respectively, in the counties of Los Angeles and Alameda, respectively, and State of California, have invented new and useful Improvements in Door-Latch-Operating Mechanism, of which the following is 10 a specification.

This invention relates to safety appliances for elevators and particularly pertains to a lock for the doors of elevator shafts and is particularly adapted for use with our controller lock mechanism disclosed in our co-pending application, filed July 27, 1916, Serial No. 111,597.

It is the principal object of this invention to provide a mechanism automatically 20 operating in connection with the power control lever of an elevator shaft and which will control the elevator shaft door lock in a manner to prevent the opening of the door when the control lever is not in a neutral 25 position.

Another object of this invention is to provide a door lock mechanism which is simple in its construction and which at all times will hold the door in its locked position 30 except at the intervals when actuated by the controller mechanism.

Another object of this invention is to provide a lock operating mechanism which is simple in its construction and which will be 35 actuated by the control lever without appreciable effort.

It is a further object of this invention to provide a safety lock for elevator doors which is at all times positive in its operation 40 and which is not liable to become broken or out of order.

Other objects will appear hereinafter.

The invention is illustrated, by way of example, in the accompanying drawings in 45 which:

Figure 1 is a fragmentary view in section and elevation illustrating an elevator car as positioned before an elevator shaft door and particularly illustrating the door lock and the control mechanism therefor.

Fig. 2 is a view in plan, as seen along the line 2-2 of Fig. 1, and as disclosing the lock actuating bar and its mode of operation.

Referring more particularly to the drawings, 50 10 indicates an elevator car, which is

adapted to move vertically along an elevator shaft. This shaft is formed with door-ways at given intervals along its length, said door-ways being closed by doors 11. The car may be driven by any source of power and is 60 here shown as controlled by a controller lever 12 which is mounted within a controller case 13 and connects with suitable control mechanism. This lever is secured to a shaft 14, around the center of which it rotates. 65 Mounted upon the wall of the elevator and adjacent the shaft is an arcuate locking bar 15 which forms a portion of the control lever locking device embodied within our co-pending application. This arcuate member is 70 pivotally mounted upon a stub-shaft 16 which is horizontally disposed above the shaft 14 of the controller and parallel therewith. The arcuate member is formed with an upwardly extending arm 17 which is provided with lever pins 18 and 19 extending along the opposite sides of the controller lever in a manner to cause the lever and the arcuate member to be actuated simultaneously.

Mounted upon the shaft 16 and fixed to rotate with the member 15 is a lifting cam 20. This cam is eccentrically mounted upon the shaft and supports a slotted lifting bar 21. The bar 21 has an enlarged upper 85 elongated slot 22 which encompasses the eccentric cam 20. The width of said slot is sufficient to permit a desired movement of the eccentric 20 and cause the bar to be raised a short distance as the controller lever and arcuate member are swung to their intermediate position. The lower portion of the bar 21 is formed with a guide slot 23 which is narrow in width and is seated over a guide roller 24 secured to the side of the 90 elevator car. Mounted upon the lower end of the bar 21 is a connecting rod 25 which depends therefrom upon a pivot pin 26 and extends through an opening in the floor of the elevator car where it is pivotally connected to a bell crank 27. This crank is mounted beneath and to the floor of the car by a bracket 28 which pivotally supports the bell crank. The leg of the bell crank to which the rod 25 is connected stands substantially horizontally and the opposite leg normally extends vertically downward. This leg is pivotally connected to a horizontally disposed connecting rod 29 which passes across and beneath the car to engage the free end of a 105

Fig. 2 is a view in plan, as seen along the line 2-2 of Fig. 1, and as disclosing the lock actuating bar and its mode of operation. Referring more particularly to the drawings, 50 10 indicates an elevator car, which is

trip lever 30. This lever is in the form of a bell crank, having legs of unequal length, the shorter of which is connected with the rod 29. The long leg is pivotally connected by a pin 31 to a lock actuating member 32. This member is formed with a horizontally extending shank 33 and a vertically extending actuating bar 34 which is horizontally moved when the trip lever 30 is rotated upon its axis. In order to guide the lock actuating member 32 and cause it to remain in position, the end of the shank 33 is provided with a pin 35 which extends into a V-shaped slot 36 formed along a guide plate 37. It will be understood that this plate also serves as a mounting for the trip lever 30 and that it is suitably secured to the sub-frame of the elevator car.

When the elevator car is in an aligned position before a doorway of the elevator shaft, the bar 34 will be in register with a hinged wear plate 38 which is dependent from its pivotal mounting upon the door lock and hangs downwardly in an interposed position between the lock bar 39 and the bar 34. This lock bar is horizontally and slidably mounted within a lock case 40 secured to the side of the elevator shaft and beneath the elevator door. The inner end of the bar is pivotally secured by a pin 41 to a counterweight lever 42 which is pivotally mounted upon a pin 43 for vertical swinging movement. The light end of the lever 42 is provided with a pin 44 which extends into a slotted opening 45 formed in the lower end of a lock-bolt 46. This bolt is slidably mounted for vertical movement within the lock case 40 and normally projects above the case and stands in an obstructing position along the horizontal path of travel of a lock lug 47. This lug is secured to the lower edge of the door 11 and when in contact with the bolt 46 prevents the opening of the door.

As previously described, the lifting bar 21 and the various connecting bars and levers interposed between the lifting bar and the trip lever 30 are inwardly actuated by the rotation of the eccentric cam 20. This movement, however, merely starts the actuation of the mechanism, which is completed by the movement of a cam finger 48 mounted to rotate with the shaft 16. This cam finger is secured to the outer face of the eccentric cam 20 and rotates therewith. The face of the cam finger encounters a roller 49 secured at the upper end of the lifting bar 21 and produces a quick upward movement of the bar the instant the controller lever 12 is brought to a vertical position, and a quick downward movement the instant the lever leaves its vertical position.

As a means for yieldably holding the actuating bar 34 in an inoperative position and also the mechanism provided to swing said

bar, a weight 50 is connected by a cable 51 to the short leg of the trip lever 30 and thereby maintains the entire mechanism in a taut condition without the use of springs and other unreliable expedients.

In operation, the elevator car is controlled by the control lever 12 which, when swung to the position indicated in Fig. 1 of the drawings, will cause the car to be raised or lowered, as determined by the control arrangement. When the car reaches a point adjacent a door 11, the controller lever is swung to a vertical position and this swinging operation will actuate the lock operating mechanism to permit the door to be slid open when the car has stopped. The movement of the lever to this neutral position first rotates the eccentric cam 20 through the medium of the arcuate lock member 15 and its arm 17. As the cam swings upon its pivot, the lifting bar 21 will be slightly raised, due to the eccentricity of the cam. As the cam reaches the height of its lift, the cam finger 48 will swing into engagement with the roller 49 and as it continues to move toward a vertical position will completely lift the bar 21. This lifting movement of the eccentric cam and the cam finger will cause the connecting rod 25 to be drawn upwardly in the direction of the arrow —a—, and the connecting rod 29 to be drawn horizontally in the direction of the arrow —b—. This movement will cause the trip lever 30 to swing in the direction indicated by the arrow —c— in Fig. 2. As this lever swings, the lock actuating member 32 will swing forwardly and the bar 34 will be brought to bear against the pivoted wear plate 38. It will be noted that as the actuating member 32 is swung by means of the trip lever, the pin at the end of its shank will pass along the V-shaped slot 36 and when the bar has pressed against the wear plate in a manner to actuate the lock bolt 46, the pin will be positioned in the upper end of the slot, as shown in dotted lines in Fig. 2.

As the actuating bar 34 moves the rod 39 inwardly, it will relieve the weight of the counterweighted arm 42 and permit the bolt to pass downwardly in a manner to clear the lug 47, thus allowing the door to be opened. When the door is closed, the controller lever 12 may then be swung from its neutral position and will relieve the lifting bar 21 so that the weight 50 will draw it to its lowermost position and swing the actuating bar from engagement with the wear plate 38 and therefore permit the locking bolt 46 to be moved upwardly by the counterweighted arm.

It will thus be seen that the door locking mechanism here provided is simple and positive in operation and is directly operated by movement of the power control lever of an elevator car.

While we have shown the preferred construction of our safety door lock for elevator shafts, as now known to us, it will be understood that various changes in the combination, construction, and arrangement of parts may be made by those skilled in the art without departing from the spirit of our invention.

We claim:

- 5 1. In a safety latch for elevators, a case adapted to project inwardly from the wall of an elevator shaft below the door, a hinged wear plate outside of the case, a lock-bar horizontally mounted with one end against the hinged wear plate and extending into the case, a counterweight pivotally mounted in the case and pivotally connected to the lock-bar, a lever extending horizontally from the counterweight, a lock-bolt mounted 10 in the case for vertical reciprocation and pivotally connected to the horizontal lever and adapted to extend out of the case to lock the door, and means carried by the elevator and connected to the controller; so 15 that when the controller is in neutral position the hinged plate will be engaged to move the lock-bar in and withdraw the lock-bolt and allow the door to be opened.
- 20 2. In a safety latch for elevators, a casing adapted to be mounted upon the inner face of the elevator shaft below the elevator door, a wear plate pivotally mounted outside of the case, a lock-bar horizontally mounted through the case and engaging the wear plate, a counterweighted lever pivotally mounted in the case and connected to the lock-bar, a latch-bolt vertically and slidably mounted in the case and connected to the counterweighted lever and adapted to engage and lock the elevator door when extended, and means carried by the elevator and connected to the controller; so that when the controller is in neutral position and the elevator near the floor level the wear 25 plate will be operated to withdraw the latch-bolt and release the elevator door.
- 30 3. In a safety latch for elevators, a controller case, a main shaft mounted horizontally in the case, a controller lever pivotally mounted on the shaft, a stub-shaft above the lever shaft, an arcuate locking bar pivotally mounted upon the stub-shaft,
- 35 an arm extending upwardly from the arcuate member, pins in the upper end of the arm, one upon each side of the controller lever, so as to actuate the arcuate member simultaneously with the controller lever, a lifting cam mounted upon the stub-shaft and fixed to rotate with the arcuate locking bar, a lifting bar having an elongated slot 40 encompassing the lifting cam and having a guide slot, a fixed guide roller for the guide slot; so that the lifting bar may be reciprocated vertically by the operation of the lifting cam; a connecting rod extending 45 from the lower end of the lifting bar through the floor of the elevator, a bell crank mounted below the floor of the elevator and attached to the connecting rod, a second connecting rod mounted horizontally 50 below the floor of the elevator and connected to the bell crank, and means operated by the second connecting rod whereby the elevator door is unlocked when the controller lever is in neutral position and the elevator 55 near the level of a floor.
4. In a safety latch for elevators, a main shaft mounted horizontally, a controller lever pivotally mounted on the main shaft, a stub-shaft above the main shaft and parallel therewith, a locking bar pivotally mounted on the stub-shaft, an arm extending upwardly from the locking bar, pins in the upper end of the arm, one upon each side of the controller lever so as to actuate the 60 locking bar simultaneously with the controller lever, a lifting cam mounted upon the stub-shaft and fixed to rotate with the locking bar, a lifting bar having an elongated slot 65 encompassing the lifting cam and having a guide slot, a fixed guide for the guide slot; so that the lifting bar may be reciprocated vertically by the operation of the lifting cam; a connecting rod extending 70 from the lower end of the lifting bar through the floor of the elevator, and means operated by the connecting rod whereby the elevator door is unlocked when the controller lever is in neutral position and the elevator 75 near the level of a floor.
- 45 5. In a safety latch for elevators, a main shaft mounted horizontally, a controller lever pivotally mounted on the main shaft, a stub-shaft above the main shaft and parallel therewith, a locking bar pivotally mounted on the stub-shaft, an arm extending upwardly from the locking bar, pins in the upper end of the arm, one upon each side of the controller lever so as to actuate the 80 locking bar simultaneously with the controller lever, a lifting cam mounted upon the stub-shaft and fixed to rotate with the locking bar, a lifting bar having an elongated slot 85 encompassing the lifting cam and having a guide slot, a fixed guide for the guide slot; so that the lifting bar may be reciprocated vertically by the operation of the lifting cam; a connecting rod extending 90 from the lower end of the lifting bar through the floor of the elevator, and means operated by the connecting rod whereby the elevator door is unlocked when the controller lever is in neutral position and the elevator 95 near the level of a floor.

In testimony whereof we have signed our names to this specification.

RICHARD J. ROULO.
